UNITED STATES PATENT OFFICE.

DONALD MCLEOD, OF TACOMA, WASHINGTON.

SCAFFOLD FOR SHIP CONSTRUCTION.

1,334,662.

Specification of Letters Patent. Patented Mar. 23, 1920.

Application filed December 23, 1918. Serial No. 267,947.

To all whom it may concern:

Be it known that I, DONALD MCLEOD, a subject of the King of Great Britain, and resident of the city of Tacoma, county of Pierce, and State of Washington, have invented certain new and useful Improvements in Scaffolds for Ship Construction, of which the following is a specification.

This invention relates to new and useful improvements in scaffolds and more particularly to scaffolds employed in ship construction and it has for its object the provision of an improved device of this nature constructed in such manner as to adapt it to support platforms of varying widths. This is desirable because the practice varies in different ship yards, with respect to the number of planks employed to constitute a platform and in addition, the fact that the sides of ships are not constructed on straight lines results in certain portions of the ship being spaced farther from the upright portion of the scaffolding than other portions thereof and it therefore becomes desirable to provide means for easily and quickly varying the extent to which the platform supporting parts of the structure project beyond the vertical portions of the scaffolding in accordance with the space available.

A further object of the invention resides in providing a structure of the character indicated which will possess the necessary rigidity when in use but will be capable of being folded to occupy a smaller space when being transported from place to place.

Further objects and advantages of the invention will be set forth in the detailed description which now follows:

40 In the accompanying drawing:

Figure 1 is a plan view of one of the scaffold brackets which constitute the platform supports;

Fig. 2 is a side elevation of the same;

45 Fig. 3 is a fragmentary side elevation showing the bracket in partly folded position;

Fig. 4 is a view similar to Fig. 3 but showing the parts in the position they occupy 50 when reversed; and

Fig. 5 is an elevation showing a number of the scaffold brackets supported upon upright members which constitute the frame of the scaffold.

55 Like numerals designate corresponding parts throughout the several figures of the drawing.

In the drawing numerals 1 designate uprights, which with the connecting transverse members 3 constitute the upright portions of the frame of the scaffold. Secured to the transverse members 3 are scaffold brackets each comprising a pair of members pivotally connected end to end, and either of which is adapted to constitute the element that is secured to the corresponding transverse member 3. In the present instance I have shown the members 4 as being secured to the transverse members 3 while the members 9 are pivotally connected to the members 4 at 13. Each of the members 4 and 9 of the bracket is formed of angle iron of L shape in cross section and the vertical portions of the members 9 project into spaces formed between the vertical portions of the members 4 and plates 6, said plates being held in spaced relation to the vertical portions of the members 4 by filling blocks 7, the several parts being tied together by rivets or other fastening devices 7'.

It will be noted by referring to Fig. 5 that the members 9 are materially shorter than the members 4, and it will also be seen that each of the members 4 and 9 is provided with openings 4^a and 9^a, respectively, which serve to receive bolts or other fastening devices, indicated at 14, by which the scaffold brackets are secured to the corresponding transverse members 3. It will be noted that by virtue of the construction described the inner ends of the vertical portions of the members 9 are brought into alignment with the filling blocks 7, and these parts are correspondingly beveled at 10 and 8, respectively, in such manner as to permit these members to be folded above the horizontal with respect to each other but not below the horizontal. Furthermore the confronting portions of the members 4 and 9 abut each other at 12 and 16 and this further aids in imparting the necessary rigidity to the structure. It is to be noted that when the scaffold brackets are attached to the transverse members 3 of the frame work of the scaffold, the pivot points 13 lie outwardly of the said uprights. If it becomes necessary to move the scaffold as a whole from one place to another the members 9 may be folded over upon the members 4 during the transportation of the scaffold.

110 It will readily be understood that when the members 4 are secured to the transverse members 3 the horizontal portions of the

members 9 constitute the supports for the planks (not shown) these planks constituting the supports upon which a workman may stand, and it will further be understood that when the members 9 are secured to the transverse members 3 by the reversal of the scaffold brackets the horizontal portions of the members 4 then constitute the support for said planks.

10 It is to be understood that the invention is not limited to the precise construction set forth but that it includes within its purview whatever changes fairly come within either the terms or the spirit of the appended claim.

15 Having thus described my invention what I claim is new and desire to protect by Letters Patent, is:

20 A scaffold comprising a structure including uprights and substantially horizontal

transverse members fixed to and uniting said uprights in combination with platform supports secured to said transverse members, each of said supports including a pair of members pivotally connected end to end in 25 such manner as to permit them to fold upwardly above the horizontal but not downwardly beyond the horizontal, the distance from the pivot point to the end of one of said members being materially greater than 30 the distance from the said pivot point to the end of the other of said members and means for attaching each of the members of the several supports to the horizontal members with the pivot point thereof lying 35 outside of the said uprights.

Signed at Seattle, Washington, this 14th day of December, 1918.

DONALD McLEOD.
